UNITED STATES PATENT OFFICE

FREDERICK H. DU VERNET, OF HAMILTON, ONTARIO, CANADA

PUMP FOR REFRIGERATING SYSTEMS

Application filed January 11, 1932. Serial No. 585,942.

This invention relates to refrigerating systems of the type wherein a gaseous fluid is compressed and expanded to produce the refrigerating effects.

5 More especially the invention relates to gas pumps for such refrigerating apparatus.

In the form of pump commonly used in such apparatus an electric motor is used to drive either a reciprocating or rotary pump.

10 This type of motor and pump produces more or less noise, none of such pumps being entirely noiseless and many of them especially when not entirely new, making very objectionable noises.

15 One important object of the present invention is to provide an improved and novel form of pump for use in connection with refrigerating systems and wherein the operation, independently of the age of the device, will be substantially noiseless.

20 A second important object of the invention is to provide a novel form of pump for this purpose wherein the formation and condensation of steam from any volatile liquid will 25 effect pumping of a gas in the refrigerating apparatus proper.

25 A third important object of the invention is to provide a novel pump of this character wherein the evaporation of the volatile liquid is effected by thermo-electric means.

30 A fourth important object of the invention is to provide a novel device of this character wherein the thermo-electric means is automatically and alternately rendered active and inactive.

35 With the above and other objects in view as will be hereinafter apparent, the invention consists in general of certain novel details of construction and combinations of parts hereinafter fully described, illustrated in the accompanying drawing and specifically claimed.

40 In the accompanying drawing the view shows a vertical section showing a pump constructed in accordance with this invention.

45 In the embodiment of the invention as herein shown there is provided a pair of vertical tubular members 10 and 11 constituting pressure columns which are connected adjacent their lower ends by a cross conduit 12 which

may be welded securely in place. The lower ends of the columns 10 and 11 are closed by plugs 13 which support bearing yokes 14 carrying idler pulleys 15. The lower parts 55 of the columns 10 and 11 and the conduit 12 are filled with a suitable liquid 16 such as oil or the like and this liquid constitutes a liquid piston which at the end in the column 10 receives the pressure of steam and at the other end presses against the gas of the refrigerating system. A float 17 floats on the liquid in the column 10 and a similar float 18 floats on the liquid in the column 11. A cord or other flexible element 19 connects these two floats and is trained around the idler pulleys 60 15.

The upper end of the column 11 is closed by a plug 20 to which are attached nipples 21 forming an outlet and an inlet for the top 70 of the column 11 and the outlet nipple carries an outwardly opening check valve 22 and the inlet nipple carries an inwardly opening check valve 23, the supply and exhaust ends of the refrigerator tube or pipe of the freezing unit being connected to these valves. 75

Adjacent the lower end of the column 10 is a boiler 24 from which extends a steam pipe 25 which leads upwardly alongside the column 10. A plug 26 fits in the top of the column 10 and screwed into this plug is the lower end of a valve casing 27 which is connected by a branch pipe 28 with the upper end of the pipe 25. Leading from this valve casing is a pipe 29 which opens into a condenser header 30. A slide valve 31 is fitted in the valve casing 27 to rest against the side from which the pipe 29 leads and this slide valve is provided with an opening 32 which, by the movement of the valve, may be brought into and out of registry with the pipe 29, being out of registry therewith when the valve is raised and in registry when the valve is lowered. A spring device 33 holds the valve 31 firmly on its seat. A series of condenser pipes or tubes 34 connect the upper header 80 to the inlet side of a valve casing 37 which has its outlet end connected to the boiler 24 by a nipple 38. In the casing 37 is a valve 39 urged toward its seat by a light spring 40. 85 Extending through a suitable opening in 90 95 100

the float 17 is a rod 41 which is connected at its upper end to a lug 42 carried by the valve 33. The lower end of this rod is provided with a collar 41' connected to a mercury switch 43 which is pivoted to a lug 44 projecting from the wall of the column 10 in such manner that the switch is closed when the rod is raised and opened when the rod is lowered. An electric heating element 45 is mounted in the boiler 24 and has terminal connections 46 leading outside the boiler. One of the terminals 46 is connected to one terminal of the switch 43 by a wire 47 and line wires 48 are connected to the remaining terminal of the switch and the remaining terminal 46.

Valved drain pipes 49 lead from the plugs 13 to the nipple 38 and baffles 50 are located in the lower parts of the columns to separate any water or condensation which may accumulate in the oil from said oil and drain it back to the water system.

In order to describe the operation of the invention it may be assumed that the float 17 is in its fully raised position and has contacted with the lug 42 to close the valve 31 and raise the switch 43 and thereby close the latter. Under these conditions the oil in column 11 will be at its lowest level and the major part of the column 11 will be filled with the refrigerant gas. Since the switch 43 is closed, current will flow through the heater element 45 and the water, which is contained in the boiler will boil. Steam under pressure will now be generated and this will force the oil down in the column 10 and up in the column 11 thereby compressing and expelling the refrigerant gas. The check valve 39 will, of course, be closed during this part of the operation. As the oil drops in column 10 the float also falls until finally it contacts with the collar 41' and pushes the rod 41 down. This opens the switch 43 and valve 31. Now the steam flows to the condenser and, the heater being cut out, no more steam is generated. The condensation of the steam lowers the pressure in the column 10 below the pressure in the column 11 so that the oil rises in column 10 and drops in column 11 which again fills with gas. The condensate passes the valve 39 as this occurs and the boiler is again filled ready for the next cycle of operations which begins as soon as the float 17 again reaches the upward limit of its movement.

It will be noted that the pressure of the gas flowing into the column 11 is caused by the absorption of heat by the gas in passing through the refrigerating coil or unit and that the greater the heat externally of the coil the faster the pressure will develop. Thus, the downflow of oil in column 11 is controlled in time by the load on the refrigerating coil and the operation is automatic in regulation.

There has thus been provided a simple and efficient device of the kind described and for the purpose specified.

It is obvious that minor changes may be made in the form and construction of the invention without departing from the material spirit thereof. It is not, therefore, desired to confine the invention to the exact form here in shown and described, but it is desired to include all such as properly come within the scope claimed.

Having thus described the invention, what is claimed as new, is:

1. A pump of the kind described, including a pair of vertical pressure columns connected at their lower ends, a liquid piston partially filling said columns and their connection, means alternately to supply steam under pressure to the upper end of one of said columns and means to condense the supplied steam, and inlet and outlet valves at the upper end of the remaining column for connection to a refrigerator unit.

2. A pump of the kind described, including a pair of vertical pressure columns connected at their lower ends, a liquid piston partially filling said columns and their connection, inlet and outlet valves at the upper end of one of the columns for connection to a refrigerator unit, means for intermittently supplying steam to the upper end of the remaining column, a condenser connected to the upper end of the last mentioned column, a condenser valve controlling flow of steam from said last column, and means for opening said valve in alternation with the supply of steam to the column and closing the valve in unison with the supply of steam.

3. A pump of the kind described, including a pair of vertical pressure columns connected at their lower ends, a liquid piston partially filling said columns and their connection, inlet and outlet valves at the upper end of one of the columns for connection to a refrigerator unit, means for intermittently supplying steam to the upper end of the remaining column, a condenser connected to the upper end of the last mentioned column, a condenser valve controlling flow of steam from said last column, a float in said last column, a valve operating rod passing through the float connected to the condenser valve, said condenser valve being arranged to open upon downward movement of the rod and close upon upward movement thereof, and a collar on said rod below said float.

4. A pump of the kind described, including a pair of vertical pressure columns connected at their lower ends, a liquid piston partially filling said columns and their connection, inlet and outlet valves at the upper end of one of the columns for connection to a refrigerator unit, a steam boiler, a pipe connection between said boiler and the upper end of the remaining column, means for intermittently

generating steam in said boiler, and means for exhausting steam from the column alternately with its generation in the boiler.

5. A pump of the kind described, including a pair of vertical pressure columns connected at their lower ends, a liquid piston partially filling said columns and their connection, inlet and outlet valves at the upper end of one of the columns for connection to a refrigerator unit, a steam boiler, a pipe connection between said boiler and the upper end of the remaining column, an electric heating unit in said boiler, means for alternately turning current on and off of said unit, and means for exhausting steam from the boiler arranged to operate during the time the current is turned off.

6. A pump of the kind described, including a pair of vertical pressure columns connected at their lower ends, a liquid piston partially filling said columns and their connection, inlet and outlet valves at the upper end of one of the columns for connection to a refrigerator unit, a steam boiler, a pipe connection between said boiler and the upper end of the remaining column, an electric heating unit in said boiler, a switch for said unit in said last column, a rod connected to said switch and arranged to close the switch as the rod is raised and to open the switch as the rod is lowered, a float in said last column through which the rod passes, and spaced stop means on said rod on opposite sides of the float for engagement by the float to move the rod.

35 7. A pump of the kind described, including a pair of vertical pressure columns connected at their lower ends, a liquid piston partially filling said columns and their connection, inlet and outlet valves at the upper end of one of the columns for connection to a refrigerator unit, a steam boiler, a pipe connection between said boiler and the upper end of the remaining column, an electric heating unit in said boiler, a switch for said unit in said last column, a rod connected to said switch and arranged to close the switch as the rod is raised and to open the switch as the rod is lowered, a float in said last column through which the rod passes, spaced stop means on said rod on opposite sides of the float for engagement by the float to move the rod, and means for exhausting steam from the boiler and arranged to operate upon each opening of the switch.

55 8. A pump of the kind described, including a pair of vertical pressure columns connected at their lower ends, a liquid piston partially filling said columns and their connection, inlet and outlet valves at the upper end of one of the columns for connection to a refrigerator unit, a steam boiler, a pipe connection between said boiler and the upper end of the remaining column, an electric heating unit in said boiler, a switch for said unit in said last column, a rod connected to said

switch and arranged to close the switch as the rod is raised and to open the switch as the rod is lowered, a float in said last column through which the rod passes, spaced stop means on said rod on opposite sides of the float for engagement by the float to move the rod, a condenser having pipe communication with the upper end of the last column and a valve controlling the communication between the column and condenser, said valve being connected to said rod and closing as the rod rises and opening as the rod is lowered.

9. A pump of the kind described, including a pair of vertical pressure columns connected at their lower ends, a liquid piston partially filling said columns and their connection, inlet and outlet valves at the upper end of one of the columns for connection to a refrigerator unit, a steam boiler, a pipe connection between said boiler and the upper end of the remaining column, an electric heating unit in said boiler, a switch for said unit in said last column, a rod connected to said switch and arranged to close the switch as the rod is raised and to open the switch as the rod is lowered, a float in said last column through which the rod passes, spaced stop means on said rod on opposite sides of the float for engagement by the float to move the rod, a condenser having pipe communication with the upper end of the last column, a valve controlling the communication between the column and condenser, said valve being connected to said rod and closing as the rod rises and opening as the rod is lowered, a pipe connecting said condenser and boiler, and a check valve in said last pipe opening toward the boiler.

In testimony whereof he has affixed his signature.

FREDERICK H. DU VERNET.
